(57) **CLAIM**

The ornamental design for a solid top for an outdoor air conditioning unit, as shown and described.

DESCRIPTION

FIG. 1 is a perspective view of a solid top for an outdoor air conditioning unit, showing our new design;

FIG. 2 is a top plane view thereof;

FIG. 3 is a front elevational view thereof, the rear being a mirror image; and,

FIG. 4 is a right side elevational view thereof, the left side being a mirror image.
